(57) **CLAIM**

The ornamental design for a motorcycle or motorcycle replica, as shown and described.

DESCRIPTION

FIG. 1 is a front and left-side perspective view of the motorcycle or motorcycle replica showing our new design;

FIG. 2 is a rear and left-side perspective view thereof;

FIG. 3 is a front and right-side perspective view thereof;

FIG. 4 is a rear and right-side perspective view thereof;

FIG. 5 is a left-side elevation view thereof;

FIG. 6 is a right-side elevation view thereof;

FIG. 7 is a rear elevation view thereof; and

FIG. 8 is a top plan view thereof.

FIG. 9 is an enlarged top, rear and right-side perspective view showing the tail portion of the motorcycle depicted in FIGS. 1-9;

FIG. 10 is an enlarged left-side elevation view thereof; and, FIG. 11 is an enlarged rear elevation view thereof.

The broken lines shown in the drawings illustrate portions of the motorcycle or motorcycle replica and environmental structure that forms no part of claimed design. The dot-dash lines shown in the drawings illustrate a boundary for the claim and form no part of the claimed design.

1 Claim, 11 Drawing Sheets
